SINGLE WHEEL COUNT MECHANISM

Lowell E. McKean, 124 E. Main St., and William Grogosza, Taylortown Road, R.D. 1, both of Shelby, Ohio

Filed Mar. 2, 1962, Ser. No. 177,091

6 Claims. (Cl. 235—118)

This invention relates to novel single wheel count mechanisms.

The primary object of the invention is the provision of simpler, more compact, more reliable, and more accurate mechanisms of the kind indicated, adapted for manual or mechanical actuation, and adapted to operate and maintain in operation other mechanisms, such as electrical switches, at selected counts, the mechanisms involving a single actuator wheel ratchet-connected to a single drive or index wheel and to a single spring return wheel, the actuator wheel, and the return wheel being rotatable on a shaft and spring-returned, and the index or drive wheel being supported non-rotatably on the shaft.

Another object of the invention is the provision of count mechanisms of the character indicated above which are designed for exceptionally long life and can be made in unusually small sizes, such as to be housed in a one-inch pipe, the wheels being formed with interengaging face type ratchet teeth, for trouble-free operation and reduction of number of wearing surfaces.

A further object of the invention is the provision of count mechanisms of the character indicated above, wherein the actuating means for the actuator wheel comprises either a rotary lever turning on the shaft carrying the wheels or an endwise movable element, both being spring-returned, the rotary lever being designed for rotating the actuator wheel more than full rotations and the endwise movable element for rotating the actuator wheel less than full rotations.

Other important objects and advantageous features of the invention will be apparent from the following description and the accompanying drawings, wherein, for purposes of illustration only, a specific form of the invention is set forth in detail.

In the drawings:

FIGURE 1 is a perspective view of a mechanism of the present invention;

FIGURE 2 is an enlarged top plan view of said mechanism, its cover being removed and parts being broken away and in section;

FIGURE 3 is a vertical longitudinal section taken on the line 3—3 of FIGURE 2;

FIGURE 4 is an exploded perspective view of the operating components of the mechanism;

FIGURE 5 is an end elevation, partly broken away and in section, of another form of mechanism of the present invention;

FIGURE 6 is a fragmentary vertical longitudinal section taken on the line 6—6 of FIGURE 5.

Referring in detail to the drawings, wherein like and related numerals designate like and related parts throughout the several views, and first to FIGURES 1 through 4, the count mechanism therein shown and generally designated 10, comprises an open-sided case composed of a bottom wall 12, a single upstanding side wall 14, and left-hand and right-hand end walls 16 and 18, respectively. The upper edges of the end walls 16 and 18 include elevated end portions, downwardly curved intermediate

2

portions, and depressed end portions, which are severally engaged by portions 26, 28 and 30, respectively, of a removable cover 32 having a pendant side wall 34 which engages the free vertical edges of the end walls and closes the open side of the case. The intermediate portion 28 of the cover 32 is provided with a central window opening 38.

A longitudinal shaft 40 is journaled through openings 42 in the case end walls 16 and 18, near the case side wall 14, and a rotary lever assembly 44 is fixed on the shaft 40, outside of the left-hand end wall 16. The lever assembly 44 comprises a sleeve 46 circumposed on and keyed to the shaft 44, as by means of a pin 48 extending through the sleeve and the shaft. The sleeve 46 has a tangential flat arm 50 fixed thereon, and adapted, when depressed from an upright position to a horizontal position, to make stop engagement with a stop pin 52 which extends outwardly from the case end wall 16 and is spaced forwardly from the shaft 40.

20 The lever assembly sleeve 46 has a notch 54, in its inward end, providing clearance for an arm 56 engaging the lever arm 50, of a coil spring 58 circumposed on the shaft 40, and having another arm 60, tensioned away from the arm 56 and having a lateral terminal 62, which is securably engaged in a hole 64, provided in the case end wall 16, above the shaft 40, whereby the lever assembly 44 and the shaft 40 are biased, in a counterclockwise direction, as seen in FIGURES 1 and 2.

25 Circumposed on the shaft 40, within the case, and successively from left to right, is a drive wheel 66, an actuator wheel 68, and a spring-return wheel 70, the wheels being preferably solid cylindrical blocks of friction-reducing, wear-resistant material, and of substantial width or length. The drive wheel 66 is keyed on the shaft 40, as by means of a pin 72 which extends through the wheel 66 into the shaft 40. A coil spring 74 is circumposed on the shaft 40 and is compressed between the case end wall 18 and the return wheel 70 and serves to maintain the wheels in yielding engagement with each other. A thrust washer 76 is on the shaft 40 between the drive wheel 66 and the case end wall 16, and a thrust washer 78 is interposed between the spring 74 and the return wheel 70. The thrust washers 80 and 82 can be interposed between the drive wheel 66 and the actuator wheel 68, and between the actuator wheel 68 and the return wheel 70, respectively, for cushioning the interengagement of their ratchet teeth.

30 The face type ratchet teeth 84, on the adjacent ends of the wheels 66, 68 and 70 are similar but reversed, and comprise acutely angled sloping circumferential faces 86 leading to right angular stop faces 88, which are parallel to the axes of the wheels. The return wheel 70 is maintained against rotation, relative to the shaft 40, and relative to the other wheels, as by means of a pin 90 threaded, as indicated at 92, in the case side wall 14 and engaged in a longitudinal groove 94 in the surface of the return wheel 70 and opening to the outer or right-hand end of the wheel 70, whereby the wheel 70 is permitted endwise movements relative to the pin 90. The actuator wheel 68 has circumferentially spaced numerals 96 on its surface, which are visible through the window opening 38 of the case cover.

35 The index or actuator wheel 68 has a radial boss 98 projecting from its surface, at a selected location relative to the count numerals 96, which is operatively engage-

able with the actuating button 100 of a switch 102 which is fixedly mounted on the case bottom wall 12, at the forward side of the wheels, whereby the switch 102 is actuated, for closing or opening an associated electrical circuit, only in a predetermined rotary position of the index wheel 68.

In operation, the lever arm 50 is pulled or pushed, in a direction away from its stop pin 52, or counterclockwise in FIGURES 1 and 2, with which it is normally engaged, a desired amount. This rotates the shaft 40 and the drive wheel 66 a corresponding amount and the ratchet teeth 84 of the drive wheel 66 ratchet over the teeth of the index wheel 68. When the lever arm 50 is then released, the spring 53 rotates the shaft 40 and the drive wheel 66, in opposite or clockwise direction, as seen in FIGURES 1 and 2, and produces engagement of the teeth of the drive wheel and the index wheel, so that the index wheel 68 is rotated in a clockwise direction to a position indicated by a corresponding numeral appearing in the window opening 38 in the case cover 32. The above described construction of the mechanism 10 enables the index wheel 68 to be rotated a full revolution by rotating the lever arm 40 a corresponding amount, away from the stop pin 52 and releasing the lever arm. As clockwise rotation of the index wheel 68 takes place, the ratchet teeth of the index wheel, facing the return wheel 70, ratchet over the teeth of the return wheel, and interengage therewith, as the rotation of the index wheel stops, so that any reverse rotation of the index wheel is positively and exactly precluded.

The form of count mechanism, shown in FIGURES 5 and 6, and generally designated 10a is adapted for operation to advance its index wheel 68 only one count at a time. The mechanism 10a is similar to the mechanism of FIGURES 1 through 4, except for a different actuating assembly 44a.

The actuating assembly 44a comprises a flat vertical rod 104 sliding through a guide opening 106, provided in the cover portion 30a and having a reduced width stem 108, on its lower end, which defines a stop shoulder 110. An expanding coil return spring 112 surrounds the stem 108 and is compressed between the shoulder 110 and a spring-positioning recess 114, provided in the case between wall 12a, whereby the rod 104 is urged upwardly. An opening 116 is provided through the rod 104, above the spring 112, which has beveled knife edges 118, through which extends freely a pin 120, fixed to and extending radially from the drive wheel 66a.

Depressing the rod 104, against the resistance of the spring 116, produces clockwise rotation of the drive wheel 66a, and upon release of the rod, the spring 116 drives the rod 104 upwardly and thereby produces counterclockwise ratchetting of the drive wheel 66a to its starting position, and hence clockwise rotation of the index wheel 68a, to the end explained hereinabove in connection with the description of the mechanism of FIGURES 1 through 4.

Although there have been shown and described preferred forms of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. In a count mechanism, a support, a shaft journaled on the support, an index wheel slidably and rotatably engaged on the shaft, said index wheel having reversed ratchet teeth on its ends, a drive wheel fixed on the shaft at one side of the index wheel and having ratchet teeth facing and interengageable with the ratchet teeth on one end of the index wheel, a return wheel slidably engaged on the shaft at the other side of the index wheel, stop means precluding rotation of the return wheel on the shaft, said return wheel having ratchet teeth facing and inter-

engageable with the ratchet teeth on the adjacent end of the index wheel, wheel-engaging spring means compressed between the support and the return wheel and yieldably urging the return wheel toward the index wheel and the index wheel toward the drive wheel, and means for rotating the drive wheel in one direction, said support comprising a case having a bottom wall, first and second end walls, and a side wall, said rotating means being positioned on the shaft outside of said first end wall, and the wheels being positioned between the end walls with the shaft journaled through the end walls.

2. In a count mechanism, a support, a shaft journaled on the support, an index wheel slidably and rotatably engaged on the shaft, said index wheel having reversed ratchet teeth on its ends, a drive wheel fixed on the shaft at one side of the index wheel and having ratchet teeth facing and interengageable with the ratchet teeth on one end of the index wheel, a return wheel slidably engaged on the shaft at the other side of the index wheel, stop means precluding rotation of the return wheel on the shaft, said return wheel having ratchet teeth facing and interengageable with the ratchet teeth on the adjacent end of the index wheel, wheel-engaging spring means compressed between the support and the return wheel and yieldably urging the return wheel toward the index wheel and the index wheel toward the drive wheel, and means for rotating the drive wheel in one direction, said support comprising a case having a bottom wall, first and second end walls, and a side wall, said rotating means being positioned on the shaft outside of said first end wall, and the wheels being positioned between the end walls with the shaft journaled through the end walls, said wheel-engaging spring means comprising a coil spring circumscribed on the shaft and compressed between the second end wall and the return wheel.

3. In a count mechanism, a support, a shaft journaled on the support, an index wheel slidably and rotatably engaged on the shaft, said index wheel having reversed ratchet teeth on its ends, a drive wheel fixed on the shaft at one side of the index wheel and having ratchet teeth facing and interengageable with the ratchet teeth on one end of the index wheel, a return wheel slidably engaged on the shaft at the other side of the index wheel, stop means precluding rotation of the return wheel on the shaft, said return wheel having ratchet teeth facing and interengageable with the ratchet teeth on the adjacent end of the index wheel, wheel-engaging spring means compressed between the support and the return wheel and yieldably urging the return wheel toward the index wheel and the index wheel toward the drive wheel, and means for rotating the drive wheel in one direction, said support comprising a case having a bottom wall, first and second end walls, and a side wall, said rotating means being positioned on the shaft outside of said first end wall, and the wheels being positioned between the end walls with the shaft journaled through the end walls, said wheel-engaging spring means being engaged with the lever arm and with said first end wall, said stop means comprising a pin extending from the case side wall, and a longitudinal groove in the periphery of the return wheel and opening to an end of the return wheel, said pin being engaged in the groove.

4. A count mechanism comprising a case having first and second end walls, and side walls, a first journal slidably through said end walls, an actuating lever fixed on the shaft adjacent to and spaced from said first end wall, a coil spring circumscribed on the shaft and compressed between said first end wall and the lever and operatively connected to the first end wall and the shaft, a stop pin on said first end wall for limiting manual rotation of the lever and the shaft, a drive wheel fixed on the shaft within the case and normally spaced from said first end wall, the side of the drive wheel remote from said first end wall having ratchet teeth thereon, an index wheel slidably and rotatably engaged on the shaft and having

ratchet teeth on the side thereof adapted to engage the ratchet teeth of the drive wheel, said index wheel having other ratchet teeth on its other side, a return wheel slidably and rotatably engaged on the shaft between the second end wall of the case and the index wheel, said return wheel having ratchet teeth adapted to engage the said other ratchet teeth of the index wheel, another coil spring circumscribed on the shaft and compressed between the second end wall and the return wheel, stop means acting between a side wall of the case and the return wheel precluding rotation of the return wheel relative to the shaft while permitting sliding of the return wheel on the shaft, and compressible thrust washers circumscribed on the shaft between the first end wall of the case and the drive wheel, between the drive wheel and the index wheel, between 15 the index wheel and the return wheel.

5. A count mechanism according to claim 4, wherein another compressible thrust washer is circumscribed on the shaft between the return wheel and said other spring.

6. A count mechanism according to claim 4, wherein 5 said index wheel has a lateral switch operating member.
